UNITED STATES PATENT OFFICE.

CHARLES HENRY BEDINGFIELD, OF MAPLE, ONTARIO, CANADA, ASSIGNOR TO
FEEDERICK CAMPBELL RUSSELL ANSLEY, OF ST. CATHERINES, ONTARIO,
CANADA.

COMBINED SPARK INTENSIFIER AND DETECTOR FOR INTERNAL-COMBUSTION ENGINES.

Application filed October 28, 1920. Serial No. 420,211.

To all whom it may concern:

Be it known that I, CHARLES HENRY BEDINGFIELD, of the village of Maple, in the county of York, in the Province of Ontario, Canada, have invented certain new and useful Improvements in Combined Spark Intensifiers and Detectors for Internal-Combustion Engines, of which the following is the specification.

10 My invention relates to improvements in spark intensifiers and detectors for internal combustion engines and the object of the invention is to devise an intensifier in which the resistance may be varied and in which 15 the resultant spark is visible for the purposes of ascertaining the correct resistance required. A further object is to provide means on each spark plug for detecting any fault therein, and a still further object is 20 to provide means whereby any defects in the circuit can be detected, irrespective of the failing of the spark plug.

My invention consists of a device constructed and arranged all as hereinafter 25 more particularly described and illustrated in the accompanying drawing in which:

Fig. 1 represents an elevation of my device showing the same applied to the spark plug of an internal combustion engine.

30 Fig. 2 is a plan view of my device.

Fig. 3 is a plan view broken away intermediately to expose the interior thereof.

Fig. 4 is a horizontal section, and

Fig. 5 is an enlarged vertical section.

35 Like characters of reference indicate corresponding parts in the different views.

1 is the shell of the spark plug. 2 is the porcelain. 3 and 4 are the ignition points. 5 is the terminal provided with the nut 6. 40 7, 8, and 9 are suitably spaced plates of insulating material such as fibre, the lower and upper plates 7 and 9 respectively being provided with the circular windows 10 and 11. 12, 13 and 14 are registering orifices in the plates 7, 8 and 9 respectively to receive the terminals 5.

45 15 is a detector finger of suitable flexible conducting material, said finger being preferably pointed at its lower end, the upper end 16 being bent over on itself and designed to straddle the lower insulating plate 7. 17 is a plate of conducting material bent back

on itself and adapted to straddle the end of the plate 9 remote from the end and having the orifice 14.

55 The intermediate plate 8 has a longitudinal slot 18 extending from one end to intermediately of the length of the plate. 19 is a slotted plate having the pointed end 20 and the turned over end 21, said plate being 60 adapted to slide in the slot 18 of the intermediate plate. 22 is a screw bolt extending through the lower plate 7, through the slot 23 in the slotted plate 19, through the portions of the plate 17 and provided above such 65 plate 17 with the locking nut 24 and the knurled nut 25.

The end of a secondary cable 26 is adapted to be inserted between the knurled nut 25 and the nut 24 and to be held in place thereby. 27 and 28 are mica plates interposed between the insulating plates 7 and 8, and 9 and 8 respectively and covering the windows 10 and 11.

70 When my device is applied to the spark plug, by pressing the finger 5 until it is very close to the shell 1 of the spark plug, with some instrument of non-conducting material such as a pencil, if the plug is in working order a spark will jump between the shell 80 and the point of the finger. If on the other hand the spark plug is "shorted" no spark will appear.

75 In using my intensifier if the magneto of the automobile is weak the plate 19 can be 85 slid longitudinally by means of the turned over end 21 until the end 20 thereof comes closer to the edge of the turned over portion of the finger 16, thus reducing the gap and consequently reducing the resistance. By 90 manipulating this movable plate the most effective gap can be determined for magnetos of different strength.

85 Visibility is essential as it is only by seeing the quality of the spark that the correct 95 setting can be determined.

If there is no spark across the gap between the pointed end 20 of the plate 19 and the adjacent edge of the upper portion 16 of the finger 15, it will indicate that the device 100 circuit is defective, exteriorly of the spark plug.

From the above description it will be seen that I have devised a simple and effective

spark intensifier and detector that can be cheaply constructed and which can be readily applied.

What I claim as my invention is:

- 5 1. In a combined spark intensifier and detector for internal combustion engines, the combination with the spark plug and the secondary cable, of spaced apart upper, intermediate and lower plates of insulating material, a fixed plate of conducting material situated between the lower and intermediate insulating plates, said conducting plate engaging the terminal of the spark plug, a movable conducting plate, means for adjusting the gap between the movable conducting plate and the fixed conducting plate, and means for connecting the movable conducting plate to the secondary cable. 45
- 10 2. In a combined spark intensifier and detector for internal combustion engines, the combination with the spark plug and the secondary cable, of spaced apart upper, intermediate and lower plates of insulating material, a fixed plate of conducting material situated between the lower and intermediate insulating plates, said conducting plate engaging the terminal of the spark plug, a movable conducting plate, means for adjusting the gap between the movable conducting plate and the fixed conducting plate, and means for connecting the movable conducting plate to the secondary cable. 50
- 15 3. In a combined spark intensifier and detector for internal combustion engines, the combination with the spark plug and the secondary cable, of spaced apart upper, intermediate and lower plates of insulating material, a fixed plate of conducting material situated between the lower and intermediate insulating plates, said conducting plate engaging the terminal of the spark plug, a movable conducting plate, means for adjusting the gap between the movable conducting plate and the fixed conducting plate, and means for connecting the movable conducting plate to the secondary cable. 55
- 20 4. A combined spark intensifier and detector for internal combustion engines comprising a detector, a finger of flexible conducting material the upper end bent back on itself, spaced apart upper, intermediate and lower plates of insulating material, the turned over end of the finger extending about one end of the lower insulating plate, 60
- 25 the intermediate insulating plate having a longitudinal slot extending from one end to intermediately of its length, a movable plate of conducting material slidable in the slot in the intermediate insulating plate, 65
- 30 said movable conducting plate having a pointed end, said upper and lower insulating plates having windows therein for exposing the extremity of the turned over upper end of the finger and the pointed end of the 70
- 35 movable conducting plate; a plate of conducting material turned over on itself straddling one end of the upper insulating plate and engaging the movable conducting plate, 75
- 40 and a terminal connection for the turned over conducting plate. 80
- 45
- 50
- 55
- 60
- 65
- 70
- 75
- 80
- 85

CHARLES HENRY BEDINGFIELD.
